BULLET.

Application filed July 5, 1921. Serial No. 482,463.

To all whom it may concern:

Be it known that we, EMIL J. KOSHOLLEK and ALOIS J. KOSHOLLEK, citizens of the United States, residing at Stevens Point, in the county of Portage and State of Wisconsin, have invented certain new and useful Improvements in Bullets; and we do declare the following to be a full, clear, and exact description of the invention, such as will enable others skilled in the art to which it appertains to make and use the same.

This invention relates to an improved bullet which is especially, although not necessarily, designed for shooting game; being, of course, adaptable for other uses.

Experience in shooting game has disclosed the fact that the ordinary jacketed type of bullet when shot to travel at modern velocity has proven, beyond a doubt, that it will not "stand up" when driven into animal tissues. The lead core in its thin plastic copper or cupro-nickel shell is too frail to accomplish the desired end, since it literally explodes and the entire bullet from point to base is practically rendered into small worthless fragments which fail to penetrate deeply enough and expend their entire energy at or near the surface of the animal, in this way causing only a superficial wound that does not kill but permits the animal to escape into the thicket to die a lingering death. Hence, a complete loss to all concerned.

The full metal cased bullet is little or no better than the one above mentioned since it penetrates clean, imparting no shock, and the hole at the point of entrance and exit is seldom much larger than the diameter of the bullet.

Modern velocities have emphatically called for a radical change in bullet construction for use in shooting game. Much study and thought has proved that what is needed is a bullet that will combine the shocking power of the ordinary jacketed type of game bullet and a high velocity, together with a bullet which has the power of the full metal cased bullet which will penetrate to the vitals of the animal regardless of where it is struck, providing, of course, that "the vitals" come in a line with the bullet's course.

In view of the foregoing circumstances, we have devised a jacketless bullet which possesses the qualities above referred to, one that really does combine the shocking power

with the ability to penetrate to a point to insure death. In short, our idea is "controlled mushrooming" which is entirely in keeping with the increase in the velocity of modern rifles from 1000 and 2000 ft. seconds to 2700 to 3000 ft. seconds.

Before proceeding further, it is desirable to point out some of the aims and features that our bullet possesses over those previously patented and marketed. Just as the soft-pointed jacketed game bullet of high speed fails to stand the impact when coming into contact with animal tissue, so they also fail to "stand up" under the terrific blow of the powder gases in the bore of the rifle which have a pressure of 45,000 to 50,000 lbs. per square inch. This extreme pressure badly deforms the base of such a bullet, allowing gas to escape unevenly at muzzle, thus giving the bullet a bad start at the muzzle and in turn causing inaccurate flight. It often happens that if such types of bullets are expanded too tightly in the bore of the gun barrel, the friction is such that it causes many troubles from split jackets, melted cores and fouling of the bore. Our bullet overcomes the above circumstances and will doubtless "stand up" under the most extreme chamber pressures now in use. It resists deformation in the bore of the rifle barrel, insures perfect delivery at the muzzle, and in this way assures accurate flight. There is absolutely no danger of any portion of the bullet remaining in the barrel as often happens with the types of bullets under discussion.

Not only has the invention the above aims in view, but it contemplates the provision of a bullet of the type set forth which is such in construction that it can be manufactured in great quantities in a small space of time by existing types of machinery, and it is thus rendered extremely inexpensive to both the manufacturer and the user.

At this point, we wish to direct attention to the fact that it is one of the very important features of this invention to provide a bullet wherein the rear end of the body is sufficiently hard to render it susceptible of readily penetrating the tissues and vitals until its entire energy is expended, and to associate with such a body a tip, which will be readily spread as soon as it strikes an obstruction, thereby curling the forward por-

tion of the body in such a way as to inflict a severe wound which practically insures instant death.

Many other features of the invention will 5 become apparent as the description goes on.

In the accompanying drawings wherein the preferred type of bullet is shown and like parts are referred to by like reference characters throughout the same:

10 Figure 1 is an elevational view of a complete bullet constructed in accordance with this invention.

Figure 2 is a central vertical sectional view through the bullet.

15 Figure 3 is a view somewhat similar to Fig. 2 showing the relative position of the parts prior to completion.

Figure 4 is an enlarged sectional view taken substantially on the plane of the line

20 4—4 of Fig. 3.

Figure 5 is a view showing how one of the bullets looks after use.

In carrying out the invention, we make use of a body 1 shaped like the types of 25 game bullets now used, the same being of any suitable calibre and being preferably composed of metal, 95% of which is copper, 4½% zinc and ½% lead, thus producing a body

30 which is comparatively hard and durable and such that it will penetrate the tissues as does the full metal cased bullet now used. If desired, this body will be provided at its inner end with a plurality of circumferentially spaced bearing rings 2. During the

35 process of manufacture of the body, we take a body of truly cylindrical form and with a suitable machinery taper the front end thereof until it assumes the shape shown in Fig. 3. Then, a bore 3 is drilled down into 40 the body from its forward end toward the center thereof leaving a comparatively thin neck 4 and a relatively thin tapered portion 5. Having done this, a lead slug 6 is placed in the bore so that its outer end terminates 45 short of the corresponding end of the body.

Now, by the use of suitable machinery, the neck 4 and adjacent portion of the tapered end of the body is crowded or contracted in such a way as to extrude the outer end of the 50 slug to provide a pointed head 7 simulating an arrow-head. Formation of this head in this manner causes the adjacent portion of the slug to become tapered as indicated at 55 8. Hence, the entire forward end of the bullet practically in to the point where the slug stops, is readily and easily destructible when brought into contact with an obstruction.

Therefore, when such an obstruction is met, this portion of the body is split in 60 such a way that it curls and assumes a shape somewhat like that indicated in Fig. 5. In this respect, our bullet is very much like the ordinary type of mushroom bullet used for game shooting. As before stated, while this 65 portion of the bullet curls up in the way

disclosed, the rear end portion of the body which is solid and resists such action, is such that it penetrates the tissues and vitals until its entire energy is expended. It is to be pointed out here that although a certain 70 process has been mentioned in the way of forming the bullet, this process can, of course, be varied; yet, it is very much preferred over any other ways known at this time for manufacturing our bullet.

75 From the foregoing description it will be seen that a bullet of considerable merit has been devised, the same being jacketless and greatly advantageous over jacketed and full metal cased types of bullet in that it possesses the qualities of strength, accuracy, penetration, and can be driven at the very highest velocity. There is no lead core to melt from the friction of the bullet with the barrel, there is no easily destructible core 80 which would change its shape from upsetting, there is no weak part which will be rendered into fragments as soon as contacting an obstruction, nor is there any part 85 to permit escape of gases or ruin the internal wall of the gun barrel in any way. The foregoing and other advantages and features of the invention have doubtless become apparent from the foregoing description and in view of this, a more lengthy and 90 detailed description is thought unnecessary.

95 Here it may be pointed out, that in Fig. 5 of the drawings we have disclosed an elevational view of a bullet which has been actually used, the same having weighed approximately 95 grains before firing and after being recovered weighing 30% less. The laceration and shock accomplished by the bullet is all that could be possibly desired and the rear portion as shown completed penetration without being disrupted to a noticeable extent. This last-named feature in an expanded game bullet is one which has long been sought by sportsmen using high velocity rifles for game shooting and will doubtless be found advantageous in view of this.

While we have shown and described a particular construction of bullet, we desire it to be understood that within the scope of the claims annexed, slight minor changes may be resorted to.

We claim:

1. A game bullet comprising a solid hard metal body having a cylindrical rear end and a tapered forward end, said last end having a socket formed therein, to render the forward portion of the body relatively thin and easily susceptible of splitting, and a solid but soft metal slug constituting a tip arranged in the socket and extending beyond the outer end thereof, the outer end of said slug being relatively small and formed with a fine point, for the purpose described

2. The process of forming a bullet capable of penetration and partial laceration consisting in forming a bore in a hard metal body at the outer end of the latter, placing 5 a soft metal slug therein so that it will terminate short of the front end of the body, and contracting the extended front end of the body to extrude the outer end of said slug to provide a tip.
- In testimony whereof we have hereunto 10 set our hands.
